United States Patent Office

Des. 185,156
Patented May 12, 1959

185,156

GLOVE

Anna M. Laux, Appleton, Wis., assignor to Zwicker Knitting Mills, Appleton, Wis., a corporation of Wisconsin

Application November 15, 1957, Serial No. 48,482

Term of patent 7 years

(Cl. D3—11)

Fig. 1.

Fig. 2.

In the drawing: Fig. 1 is a front view of a glove showing my new design as it appears with the thumb turned downwardly against the lower portion of the glove; and Fig. 2 is a rear view of the glove shown in Fig. 1 as it appears with the thumb turned upwardly.

I claim:

The ornamental design for a glove, substantially as shown.
